UNITED STATES PATENT OFFICE.

JOHN E. MITCHELL AND DENNIS PARKS, OF ST. LOUIS, MISSOURI.

HEEL-BLANK BUILDING.

1,399,508.

Specification of Letters Patent.

Patented Dec. 6, 1921.

Application filed December 23, 1920. Serial No. 432,695.

To all whom it may concern:

Be it known that we, JOHN E. MITCHELL and DENNIS PARKS, citizens of the United States, residing in the city of St. Louis and 5 State of Missouri, have invented new and useful Improvements in Heel-Blank Building, of which the following is a specification.

This invention relates to the art of heel-blank building and has for its general object 10 the provision of a novel machine and the employment of a novel method to be followed preferably by the use of said machine, whereby heel-blanks may be assembled and forced into a log-holder, a separating member being 15 disposed between the heel-blanks, and the heel-blanks and separating members being successively separated from the end of the log and returned to a position within the reach of the operator. By the use of such 20 a machine, and by the practice of such a method, it is made possible to reduce the number of separating plates employed to the minimum, because the returned separating members may be continuously re-used.

25 The general method involved is set forth in patents of Dennis Parks, No. 1,383,846, July 5, 1921, and No. 1,381,735, June 14, 1921. In the commercial practice of these methods, as well as in other instances in the prior 30 art where heel-blanks are maintained in column formation in a log-holder until the setting of the paste between the lifts, the log-holder extends downward, and frequently through an opening in the floor where the 35 operator builds the heels, to a lower floor, or, in some cases, it may extend through two or three floors. The use of such log-holders necessitates the employment of quite a large number of separating members which, in the 40 present case, and in the case of the Parks methods referred to, are of the general form illustrated in the Parks Patent No. 1,381,735.

This is due to the fact that with a relatively 45 long log-holder, a large number of separating members will be embodied in the log before the heel-blanks will begin to be discharged from the lower end of the holder. Where the log-holder extends through one or more floors, considerable time must elapse 50 before a sufficient number of the members have been collected on the lower floor to warrant a helper in making a trip to the upper floor to return them to the operator. These 55 separating members are of metal and as different sizes of separating members must be employed for different sizes of heel-blanks,

the number of these separating members which must ordinarily be maintained in stock, especially where a number of machines are employed, is very considerable, and has 60 proven quite objectionable.

The objection above alluded to has been overcome by the machine involved in the subject-matter of the present invention, in which the log-holder is constructed so as to return 65 the blanks to the operator; in the present instance it is disposed upwardly instead of downwardly and is provided with a return bend and an extension terminating near the operator whereby, as stated above, the finished heel-blanks and separating members 70 will be continuously returned to a position within the reach of the operator, so that the same separating members may be used over and over again; and as the log-holder need 75 not be of any considerable length, only a relatively small number of separating members need be employed.

The invention is illustrated in the accompanying drawing, in which—

80 Figure 1 is a view partly in elevation and partly in section of a machine constructed according to the invention; and

Fig. 2 is a view in front elevation of the machine, a part thereof being broken away 85 to better illustrate the construction.

Referring now to the drawings, the numeral 1 indicates the base of the machine from which extends an upright frame 2 enclosing or supporting the main elements of 90 the machine. Mounted in the upper part of the frame 2 is a drive shaft 3 provided with a pulley 4 which is driven from a belt 5 from any suitable source of power. Mounted on the shaft 3 is an eccentric 6, carrying an 95 eccentric strap 7, and eccentric rod 8 producing certain operations hereinafter described.

The forward side of the frame 2 in its upper portion is shaped to provide two 100 frame supports 9, 10, upon which is mounted in the inclined position shown in Fig. 1, a log-holder 11. This log-holder, as usual, comprises a breast-plate 12 for supporting the breast side of the heel-blank and a back-plate 13 usually of triangular cross-section, for receiving the rounded portion of the heel-blank. The end of the log-holder is so constructed as to offer a resistance to the passage of the log. This is accomplished by 105 means of a lateral extension preferably in the form of a return-bend. The log-holder

may extend upwardly in an inclined direction. The breast-plate 12 constitutes the lower member of the log-holder and at its upper end there is secured to its underside, 5 an upwardly curved or upwardly directed extension 14, the upper end of which forms the upper terminus of a chute 15 open on its upper side and secured in any suitable manner, as by being bolted to the upper side of 10 the log-holder 11 and extending from the curved member 14 to a point near the lower end of the log-holder. Secured over the chute 15 at any convenient distance therefrom, is a cover plate 16, the same being 15 secured to the chute 15 by light frames 17. Near its lower end on its underside, the cover plate is provided with a pivoted plate or swinging door 18 extending down into the chute 15, and normally resting on the 20 bottom thereof, the purpose of which is to retard the movement of the heel-blanks as they slide down chute or trough 15 and prevent them from jumping or bouncing out of the trough. At the upper end of the bottom 25 of the trough 15, which terminates short of the ends of the sides of the trough, is pivotally mounted a gate 18^a which extends beyond the upper end of the back plate 13 and constitutes one wall of a curved passage 18^b 30 formed by said gate and the curved extension 14. The lower end of the trough is closed and its lower end portion is enlarged so as to form a chamber as indicated at 19 in Fig. 2, to accommodate a number of heel-blanks and separating members.

Pivottally mounted at 20 is an actuating member in the form of a lever 21 composed of two parallel bars between the upper ends of which is pivotally mounted a slide-block 40 22 provided at its upper end with an up-standing flange or plate 23 against which the lifts are built up. A suitable mark or other indication (not illustrated) is provided on the breast plate 12 adjacent to the plate 23 45 to determine the height to which the heel-blank is to be built up. Extending over the log-holder 11 and secured thereto about centrally of its length is a yoke or saddle 24 to which is pivotally secured one arm of a bell-crank lever 25 that is pivoted on the frame 50 2. The other arm of said lever is connected to one end of a rod 26, the opposite end of which extends through the lower frame-support 10 and is screwthreaded to receive an 55 end screw 27. By turning this end screw, the bell crank may be adjusted in one direction or the other to raise or lower the back plate 13 relative to the breast plate 12 of the log-holder to vary the cross-sectional area 60 thereof in accordance with the size of the heel-blank being built at any given time. Secured on the lower end of the eccentric rod 8 before referred to, is a dog-frame or yoke 28 providing an opening or wide slot 65 29 for receiving a lug 30 projecting from the

side of the lever 21 at its upper portion, and the upper end 31 of the frame is enlarged or offset downwardly so as to form a shoulder 32. Mounted on the underside of the yoke 28 near the lower end thereof is a friction roller 33. Pivotally mounted substantially centrally of its length on a cross rod 34, is a bell-crank lever 35 having a depending arm 36 to the lower end of which is pivotally connected a pull rod 37, the other end 70 of the pull rod being pivotally connected to a throw-lever 38 secured at its lower end on a rock shaft 39 mounted in bearings 40 on the base 1. Pivotally mounted on the shaft 39 is a controlling lever to be operated at 80 will. This may be in the form of a treadle 41 provided at its inner end with dogs 42 and 43, one or the other of which is adapted to engage one end of a pawl 44 pivotally mounted at 45 on the side of the throw-lever 85 38. If the operator is standing, the dog 42 will be placed in engagement with the pawl 44. If the operator is sitting, the dog 43 will be engaged with the pawl to raise the treadle into position convenient of access. 90 The other arm 46 of the bell-crank lever 35 extends upwardly and forwardly in the general direction of the lever 21 when the latter is in its normal position, and is provided at its upper end, on opposite sides, with two 95 pivoted hooks 47 which are adapted to engage a cross-bar 48 extending between the two arms of the lever 21.

In the operation of this machine it should be understood that the yoke or dog-frame 100 28 is constantly reciprocating. The mechanism which is controlled by the treadle 41 is constructed in such a way that when the treadle is depressed, the lever 21 will be moved forwardly sufficiently to enable the 105 lug 30 to come opposite to the path of movement of the shoulder 32; and the construction is such that when the lug comes into this position, the yoke 28 rises automatically so that the shoulder 32 will engage the lug 110 30, and the rest of the inward movement of the lever 21 will be performed by power, that is, automatically by the machine itself. In order to accomplish this we prefer to provide a guide which is flexibly held in 115 position. In the normal position of this guide, the yoke 28 reciprocates in a depressed position, but when the treadle is actuated the guide moves upwardly or inwardly as the lever 21 is advanced by the 120 treadle. This guide is preferably in the form of an arm 49, the inner end of which is pivoted at 50 to the upper end of the arm 46 of the bell-crank lever. The lower or outer end of this guide 49 is turned upwardly to form a cam 51. The arm 49 is actually a part of a bell crank lever, the short arm 52 of which extends along the edge of the upper end of the arm 46. A 125 flexible and resilient connection is provided 130

which will permit the guide 49 to be deflected downwardly if sufficient force is exerted upon its upper side. For this purpose the upper or inner edge of the arm 46 is provided with a long bolt 53 which extends through the arm 52 and carries a coil spring 54; the lower end of which thrusts against the arm 52; so as to press it toward the arm 46. The arm 52 carries an adjusting screw 55 the end of which abuts against the edge of the arm 46 to determine the position in which the arm 49 will be held by the spring. It will be evident that the hooks 47 operate as a one-way connection between the arm 46 and the lever 21, that is to say, while they enable upward or forward movement of the arm 46 to advance the lever 21 into the position from which it will be advanced automatically by the yoke 28, the hooks 47 will not prevent the independent movement of the lever 21 when it is being actuated by the eccentric rod 8.

An adjustable stop is provided for determining the extreme rearward position of the lever 21. For this purpose we may provide a simple threaded adjusting stem 56 (see Fig. 1), which extends through the frame support 10 so that its forward end abuts against the rear edge of the lever 21. The fact that this stop is adjustable, facilitates the building of heels of different heights, for it is evident that by adjusting the screw, the distance from the plate 23 to the fixed mark (referred to above) on the breast plate 12 can be regulated. And in the operation of the machine the lifts will be set in place until the uppermost lift comes opposite the fixed mark. In Fig. 1, 57 indicates the heel-blanks, and the drawing illustrates the manner in which they are embodied into a column lying in the log-holder, the adjacent blanks being separated by the separating members or separators 58 referred to above.

It should be understood that as each heel-blank is completely formed, it is shoved up by the slide-block 22 against the lower end of the column and the entire column is then shoved upwardly in the log-holder. It is necessary to have a considerable resistance to this movement of the log, in order to secure the proper degree of compression of the heel-blanks, and this resistance is secured by adjusting the back-plate 13, so that it will offer the requisite frictional resistance to the movement of the column of blanks through the holder.

A light coil spring 59 is provided which nearly counterbalances the weight of the lever 21 to which it is attached, the other end of the spring being provided with an adjusting stem 60 passing through the wall of the frame and carrying a wing-nut 61 for adjusting the same.

The general mode of operation of the entire machine will now be briefly stated.

As the shaft 3 revolves, the eccentric 6 reciprocates the eccentric rod 8 and the dog-frame or yoke 28 reciprocates, being guided by the roller 33 which runs on the upper side of the guide arm 49. In the position of the treadle 41 indicated in full lines, the yoke or dog-frame 28 will reciprocate without affecting the lever 21 in any way. After the operator has built up a heel-blank to the desired height, he places a separator 58 thereon and depresses the treadle 41. This actuates the bell-crank lever 35 and swings the arm 36 thereof upwardly; through the hooks 47 this operates to swing the lever 21 upwardly. If the yoke 28 happens to be in the most outward position of its reciprocating travel, the action of the cam 51 will be to raise the yoke 28 as soon as the lug 30 has advanced far enough for the shoulder 32 to come up behind it; the eccentric rod 8 will then pull the yoke or dog-frame 28 up, thereby swinging the lever 21 upward and shoving the newly formed heel-blank and separator into the holder. If the yoke 28 happens to be in the position in which it is shown in Fig. 1, when the treadle 41 is depressed, the forward movement of the arm 49 will set it in position so that on the next up-stroke of yoke 28 the shoulder 32 will catch the lug 30. In the operation of the arm 49 the spring 54 is useful, because it prevents any possibility of injury to the mechanism by a faulty adjustment of the parts and if the arm 49 should be thrown over by the treadle at a time when the lug 30 would not permit the yoke to rise, then the spring 54 would simply be compressed slightly by a downward movement of the arm 49 under the action of the roller 33, and as soon as the lug 30 would permit the yoke 28 to rise, the spring would then operate to shove it up through its action on the arm 49. As each heel-blank is added to the log the upper heel-blanks and their separators will be forced around the curved extension 14 into the chute 15 and will descend into the chute chamber at 19 within the reach of the operator who can then remove them and use the separators over again in forming new heel-blanks.

We claim:

1. The method of successively detaching heel-blanks temporarily maintained in column formation, which consists in advancing the column of blanks in stages and continuously forcing one end of the column of heel-blanks in a path diverging from that of the column, in such manner as to bodily deflect each blank in turn from the column without disturbing the relative positions of the assembled lifts composing the blank.

2. The method of successively detaching

- heel-blanks temporarily maintained in column formation, which consists in advancing the column of blanks in stages in a right line and continuously forcing one end of the column of heel-blanks in a curved path in such manner as to bodily deflect each blank in turn from the column without disturbing the relative positions of the assembled lifts composing the blank.
10. 3. The method which consists in supporting a column of heel-blanks and separators in an inclined position, adding heel-blanks and separators in succession at the lower end of the column, forcing the entire column upwardly after the addition of each heel-blank and separator, directing the upper end of the column laterally to effect detachment of the heel-blanks and separators in succession from the column, and permitting the blanks and separators to return by gravity to a point near the lower end of the column.
4. In the art of heel-building, the method which consists in forming a column of heel-blanks and interposed separators by successively forcing in alternation a heel-blank and a separator in an upward direction through a zone of frictional resistance, separating each heel-blank and its separator from the column as they pass out of said zone, and effecting the return of the separators to the region of the initial operation.
5. In the art of heel-building, the method which consists in forming a column of heel-blanks and interposed separators by successively forcing in alternation a heel-blank and a separator in an upward direction through a zone of frictional resistance, changing the direction of movement of said blanks and separators as they emerge from said zone and returning the separators to the region of the initial operation.
6. In the art of heel-building, the method which consists in forming a column of heel-blanks and interposed separators by successively forcing in alternation a heel-blank and a separator in an upward direction through a zone of frictional resistance, causing the heel-blanks and separators to travel in a curved path as they emerge from said zone and thereby to be separated from said column, and returning said separators by gravity to the region of the initial operation.
7. In the art of heel-building, the method which consists in forming a column of heel-blanks and interposed separators by successively forcing in alternation a heel-blank and a separator in an upward direction through a zone of frictional resistance, causing the heel-blanks and separating members to travel in an upwardly curved path as they emerge from said zone and thereby to be separated from said column, and simultane-

ously with such movement delivering the heel-blanks and separators detached from said column upon an inclined path whereby they may return by gravity to the region of the initial operation.

8. In a machine of the class described, the combination of a holder for a series of heel-blanks and separators in column formation, means for forcing successive blanks and separators into the holder at one end thereof, and a lateral extension at the remote end of the holder for guiding the blanks and separators laterally and effecting their successive detachment from the column.

9. In a machine of the class described, the combination of a holder for a series of heel-blanks and separators in column formation, means for forcing the blanks and separators successively into the holder at one end thereof, a lateral extension at the remote end of the holder for guiding the blanks laterally and effecting their successive detachment from the column, and means for returning the separators to a point near the entrance end of the holder.

10. In a heel-building machine, the combination of a log-holder for receiving a column of heel-blanks and separators, means for forcing the blanks and separators into the holder at the feeding end thereof, an elbow guide disposed at the remote end of the holder for guiding the blanks and separators laterally, and means for effecting the return of the heel-blanks and separators to a point near the feeding end of the log-holder.

11. In a machine of the class described, the combination of an upwardly inclined holder for a series of heel-blanks and separators in column formation, means for forcing the blanks and separators successively into the holder at the lower end thereof, a lateral extension at the upper end of the holder for guiding the blanks laterally and effecting their successive detachment from the column, and means for returning the detached separators to a point near the lower end of the holder.

12. In a heel-building machine, the combination of an upwardly inclined log-holder, a heel-blank forcing member disposed adjacent the lower end of the log-holder, means for moving the same to successively force heel-blanks and separators into the log-holder, means at the upper end of the log-holder for guiding the heel-blanks and separators laterally, and a chute for returning the separators thereafter to a point near the lower end of the log-holder.

In testimony whereof, we have hereunto set our hands.

JOHN E. MITCHELL.
DENNIS PARKS.
